FIG. 1

FIG. 2

FIG. 3

FIG. 4

FIG. 5

FIG. 6

FIG. 1 is a perspective view of an illuminable book-end stand or the like embodying my new design;

FIG. 2 is a front elevational view thereof;

FIG. 3 is a side elevational view thereof;

FIG. 4 is a rear elevational view thereof;

FIG. 5 is a top plan view thereof; and

FIG. 6 is a left hand elevational view thereof illustrating the opposite side of that shown in FIG. 3.

The design is characterized by the combination of the bookstand disclosed having a beveled base and relatively wide illuminable square support members inset from the outer margins of said base and having externally pro-

jecting framed members of the outer end faces of the uprights, all as shown.

I claim:

The ornamental design for an illuminable book-end stand, as shown and described.
